VACUUM ATTACHMENT FOR ELECTRIC HAIR CLIPPER

Clifford H. Jording and John F. Wahl, Sterling, Ill., assignors to Wahl Clipper Corporation, Sterling, Ill., a corporation of Illinois

Filed Mar. 7, 1966, Ser. No. 1,332

Term of patent 14 years

(Cl. D9—2)

FIG. 1

FIG. 2

FIG. 3

FIG. 4

FIG. 5

FIG. 6

FIG. 1 is a perspective view of a vacuum attachment for electric hair clipper embodying our new design, the broken line showing the hair clipper being for purposes of illustration only.

FIG. 2 is an elevational view of one side thereof, the appearance of the other side being similar.

FIG. 3 is a top plan view thereof.

FIG. 4 is a bottom view thereof.

FIG. 5 is a front elevational view thereof.

FIG. 6 is a rear elevational view thereof.

We claim:

The ornamental design for a vacuum attachment for electric hair clipper, as shown and described.
